ALKYLATION OF HYDROCARBONS

Ernest F. Pevere, Beacon, Louis A. Clarke, Fishkill, and George B. Hatch and Frank H. Bruner, Beacon, N. Y., assignors, by mesne assignments, to The Texas Company, New York, N. Y., a corporation of Delaware

No Drawing. Application May 13, 1939,
Serial No. 273,574

15 Claims. (Cl. 260—683.4)

This invention relates to the manufacture of motor fuels and has to do particularly with the production of high anti-knock motor fuels, such as gasoline, by the reaction of isoparaffins, for example, isobutane, with oxygenated hydrocarbon compounds in the presence of an alkylation catalyst, such as sulphuric acid.

The invention broadly contemplates reacting isoparaffins with an oxygenated hydrocarbon, such as alcohols and ethers, in the presence of an alkylation catalyst, such as concentrated sulphuric acid.

In pending application, Serial No. 148,978, on which Patent No. 2,260,945 has now issued on a divisional application thereof, alkylation of isoparaffin hydrocarbons with olefin hydrocarbons in the presence of concentrated sulphuric acid is disclosed. This alkylation reaction results in the production of saturated gasoline hydrocarbons of high anti-knock value.

We have discovered that gasoline hydrocarbons of high anti-knock value may be prepared by reacting isoparaffins, such as isobutane, with oxygenated hydrocarbons in the presence of concentrated sulphuric acid. These oxygenated hydrocarbons comprise aliphatic and hydroaromatic alcohols and aliphatic ethers.

While alcohols having less than about three carbon atoms in the molecule do not appear to alkylate satisfactorily under the usual conditions of temperature which can be employed without objectionable deterioration of sulphuric acid as a catalyst, we have found that aliphatic alcohols having from about three to ten carbon atoms are particularly suitable for alkylation in the presence of sulphuric acid to produce a product within the gasoline boiling range. Higher molecular weight alcohols may be alkylated also for the production of a product suitable as a safety fuel. Ethers corresponding to these alcohols, for example, butyl ether corresponding to normal butyl alcohol, isopropyl ether corresponding to isopropyl alcohol, etc., may likewise be alkylated.

Somewhat different conditions of alkylation are desirable for the different alcohols and ethers. In general, the primary alcohols require higher temperatures than the secondary and tertiary alcohols; and the lower molecular weight alcohols require higher temperatures than the higher molecular weight alcohols.

It has also been found that the addition of a small amount of a material, such as butylenes or polymers thereof, and secondary or tertiary alcohols of four or more carbon atoms, effect a promoting action in the alkylation of the alcohols and ethers, enabling the reaction to be carried out at normal or nearly normal temperatures in a large number of instances where elevated temperatures would otherwise be required. In some instances the presence of a promoter is quite essential in order for the reaction to proceed. The

amount of promoter used may vary from about 5 to 15% by weight of oxygenated hydrocarbon feed, although higher proportions can be used.

As indicated in the table presented below, a number of these alcohols were reacted with isobutane in the presence of sulphuric acid having a concentration of 98% H_2SO_4 . The reaction was carried out at the temperature indicated, obtaining the indicated yield of product.

The general procedure followed in making these experiments involved charging the acid and isobutane to a reaction bomb provided with means for maintaining the contents at a desired temperature. While subjecting the contents to stirring the alcohol was introduced at the rate of about 100 cubic centimeters per hour. After the desired amount of alcohol had been added agitation was continued for about 30 minutes. The reaction product, after removal of the used acid, was transferred to a stabilizer or distilling column. The temperature at the top of the column was maintained at about 41° F., while the temperature at the bottom was maintained at 120° F. in order to remove the gaseous constituents.

The stabilized product was then withdrawn, measured and washed with caustic soda and the washed material then subjected to distillation to obtain the gasoline fraction boiling up to an end point of 311° F.:

30	Alcohol	Temp., °F.	Yield, percent by volume-basis alcohol	
			Total reaction product	Fraction boiling up to 311° F. end point
35	Isopropyl	50	16.9	-----
	Isopropyl in the presence of a promoter ¹	110	132.3	117.6
40	Normal butyl	50	Nil	Nil.
	Normal butyl in the presence of a promoter ²	135	126.4	112.0
	Isobutyl	50	56.8	-----
	Secondary butyl	45	144.5	124.1
	Tertiary butyl	50	133.9	117.3
	Normal amyl	140	131.3	119.3
	Iso amyl	70	Nil	-----
	Do	120	152.4	140.0
45	Secondary butyl carbinol	120	158.3	144.0
	Diethyl carbinol	70	112.2	79.5
	Methyl propyl carbinol	80	136.8	104.2
	Tertiary amyl	70	167.8	144.0
	Normal hexyl	70	Nil	-----
	Do	120	113.6	92.6
50	Do	140	118.6	104.6
	Methyl isopropyl carbinol	75	154.0	121.9
	2ethyl hexanol	102	151.6	120.2
	Cyclohexanol	100	106.6	-----

¹ 10% trisobutylene by weight of the alcohol.

² 10% diisobutylene by weight of the alcohol.

55 The corresponding ethers can also be alkylated with isobutane, obtaining satisfactory yields. For example, isopropyl ether was reacted with isobutane in the presence of 10% trisobutylene by weight of the ether, at a temperature of around 130° F. From a charge mixture containing 80

grams of the ether and 3 grams of the promoter 150 grams of total reaction product were obtained. In the absence of the butylene polymer a higher temperature is required as in the case of the alcohols.

As indicated from the foregoing tabulation, the reaction temperatures may range from around 45 to 140° F. and slightly above. It is contemplated carrying out the reaction, using approximately a 2:1 isobutane alcohol ratio and a 4:1 acid/alcohol ratio. However, the ratio of isobutane to alcohol may be varied from about 1:1 to 6:1 or over, while the ratio of acid to alcohol may be varied from about 2:1 up to 5:1 or over. The concentration of the sulphuric acid catalyst ranges from around 90 to 100% H_2SO_4 .

It is contemplated that the alcohol or other oxygenated compound to be used in the alkylation reaction may be derived from different sources. For example, it may be obtained from the treatment of oxidized or halogenated petroleum hydrocarbons, or it may be obtained by known methods of treating olefin containing hydrocarbon gases with sulphuric acid.

While concentrated sulphuric acid has been referred to as the alkylation catalyst, it is contemplated that other alkylation catalysts, which are effective for the ordinary atmospheric temperature alkylation of isoparaffins with olefins may be employed, such as aluminum chloride and a liquid BF_3 -water complex. The BF_3 -water complex comprises a liquid formed by completely or substantially saturating water with boron trifluoride at around normal temperature, producing a liquid analyzing $BF_3 \cdot nH_2O$, where n is about 1 to 1.5.

Obviously many modifications and variations of the invention, as hereinbefore set forth, may be made without departing from the spirit and scope thereof, and therefore only such limitations should be imposed as are indicated in the appended claims.

We claim:

1. The method of manufacturing saturated motor fuel hydrocarbons from an aliphatic alcohol having from three to ten carbon atoms, which comprises reacting the alcohol with a low boiling isoparaffin hydrocarbon in the presence of concentrated sulphuric acid at a temperature of about 45 to 140° F., and maintaining a substantial molar excess of isoparaffin in the reaction so as to convert the alcohol to a reaction product containing a substantial proportion of gasoline hydrocarbons of high antiknock value.

2. The method of manufacturing motor fuel hydrocarbons of high antiknock value which comprises subjecting a low boiling isoparaffin hydrocarbon and an oxygenated hydrocarbon selected from the group consisting of aliphatic and hydro-aromatic alcohols having from 3 to 10 carbon atoms per molecule and the corresponding aliphatic ethers to contact at ordinary atmospheric temperatures and not in excess of about 140° F. with an alkylation catalyst effective for the ordinary atmospheric temperature alkylation of isoparaffins with olefins, and maintaining a substantial molar excess of isoparaffin in the reaction whereby substantial alkylation of the isoparaffin occurs to produce gasoline hydrocarbons of high antiknock value.

3. The method according to claim 2 in which the isoparaffin hydrocarbon comprises isobutane.

4. The method of manufacturing saturated motor fuel hydrocarbons from an oxygenated hydrocarbon selected from the group consisting of aliphatic and hydro-aromatic alcohols having from 3 to 10 carbon atoms per molecule and the corresponding aliphatic ethers which comprises reacting the oxygenated hydrocarbon with a low boiling isoparaffin hydrocarbon in the presence of strong sulfuric acid of alkylation strength at a temperature of about 45 to 140° F. and maintaining a substantial molar excess of isoparaffin over oxygenated hydrocarbon in the reaction so as to convert the oxygenated hydrocarbon to a reaction product containing a substantial proportion of gasoline hydrocarbons of high antiknock value.

5. The method of manufacturing saturated motor fuel hydrocarbons from an oxygenated hydrocarbon selected from the group consisting of aliphatic and hydro-aromatic alcohols having from 3 to 10 carbon atoms per molecule and the corresponding aliphatic ethers which comprises reacting the oxygenated hydrocarbon with a low boiling isoparaffin hydrocarbon in the presence of strong sulfuric acid of about 90-100% strength, and maintaining a substantial molar excess of isoparaffin hydrocarbon present in the reaction thereby converting the oxygenated hydrocarbon to a reaction product containing a substantial proportion of gasoline hydrocarbons of high antiknock value.

6. The method according to claim 5 in which the reaction is effected in the presence of a promoter selected from the group consisting of butylenes, and butylene polymers.

7. The method according to claim 5 in which the isoparaffin hydrocarbon comprises isobutane.

8. The method according to claim 5 in which the oxygenated hydrocarbon comprises isopropyl alcohol.

9. The method according to claim 5 in which the oxygenated hydrocarbon comprises tertiary butyl alcohol.

10. The method of manufacturing saturated motor fuel hydrocarbons which comprises contacting isopropyl alcohol with a low-boiling isoparaffin hydrocarbon in the presence of concentrated sulfuric acid and maintaining a substantial molar excess of isoparaffin hydrocarbon with respect to the alcohol during the contacting.

11. The method of manufacturing saturated motor fuel hydrocarbons which comprises contacting tertiary butyl alcohol with a low-boiling isoparaffin hydrocarbon in the presence of concentrated sulfuric acid and maintaining a substantial molar excess of isoparaffin hydrocarbon with respect to the alcohol during the contacting.

12. A process for the production of high octane number hydrocarbon fuels comprising reacting an isoparaffinic hydrocarbon with isopropyl alcohol in the presence of strong sulfuric acid under alkylating conditions.

13. The method of manufacturing substantially-saturated motor fuel hydrocarbons which comprises contacting an isoparaffinic hydrocarbon with an aliphatic alcohol having from four to five carbon atoms to the molecule in the presence of strong sulfuric acid catalyst under conditions effective to produce a substantial yield of substantially-saturated motor fuel hydrocarbons.

14. The method of manufacturing substantially-saturated motor fuel hydrocarbons which comprises reacting a low-boiling isoparaffin with a non-primary aliphatic alcohol having from three to five carbon atoms to the molecule in the presence of strong sulfuric acid under alkylating conditions.

15. The method of manufacturing substantially-saturated motor fuel hydrocarbons which

comprises reacting an isoparaffin with an oxygenated hydrocarbon selected from the group consisting of aliphatic and hydroaromatic alcohols having from three to ten carbon atoms per molecule and the corresponding aliphatic ethers under alkylating conditions including normal atmospheric temperatures below about 140° F. in

the presence of an alkylation catalyst effective for the ordinary atmospheric temperature alkylation of isoparaffins with olefins.
